UNITED STATES PATENT OFFICE.

GEORGE R. SHEALY AND JOHN K. DERRICK, OF LITTLE MOUNTAIN, SOUTH CAROLINA.

HOLDER.

Application filed April 9, 1925. Serial No. 21,913.

To all whom it may concern:

Be it known that we, GEORGE R. SHEALY and JOHN K. DERRICK, citizens of the United States, residing at Little Mountain, in the 5 county of Newberry and State of South Carolina, have invented certain new and useful Improvements in Holders, of which the following is a specification.

This invention relates to a holder, 10 designed primarily for holding or suspending brooms, but it is to be understood that a holder, in accordance with this invention, can be employed for any purposes for which it is found applicable, and the invention has 15 for its object to provide, in a manner as hereinafter set forth, a simple, durable and comparatively inexpensive holder for supporting a large number of brooms and capable of enabling the same to be advantageously displayed.

A further object of the invention is to provide, in a manner as hereinafter set forth, a holder for the purpose referred to, which will enable the article or articles held and 25 suspended thereby to be readily removed therefrom, when occasion requires.

A further object of the invention is to provide, in a manner as hereinafter set forth, a holder for the purpose referred to, 30 with counter-balanced elements for normally maintaining the articles suspended thereby in vertical position to completely display the same.

Further objects of the invention are to 35 provide, in a manner as hereinafter set forth, a holder for the purpose referred to, which is strong, compact, thoroughly efficient and convenient in its use, readily assembled, and inexpensive to manufacture.

With the foregoing and other objects in view, the invention consists of the novel construction, combination and arrangement of parts, as hereinafter more specifically described and illustrated in the accompanying 45 drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a top plan view of a holder, in accordance with this invention.

Figure 2 is a side elevation thereof.

Figure 3 is a fragmentary view, in sec-

tion, illustrating one of the counter-balancing elements supporting a broom vertically, the handle of the broom being illustrated in dotted lines.

Figure 4 is a fragmentary view, in top plan, illustrating one of the counter-balanced article supporting elements.

Figure 5 is a fragmentary view, in section, illustrating the spacing means for the sections of the body portion of the holder.

The holder includes a sectional body portion of any suitable contour, preferably circular, and as illustrated of circular contour and formed of an inner section 1 and an outer section 2. Each of the sections is constructed from a length of wire, arranged in circular form. The sections 1 and 2 are concentrically arranged with respect to each other in spaced relation, and permanently maintained in such relation through the medium of a plurality of hangers and spacing blocks secured together and connected with the sections 1, 2.

The number of spacing blocks corresponds to the number of hangers and each of said blocks is of the desired length and indicated at 3. The forward end of the block 3 is bevelled, as at 4, and the upper inner corner of the block 3 is cut away to form a curved seat 5. The block 3 is formed with a longitudinally extending opening 6 of the same length as the length of the block.

Each of the hangers is indicated at 7 and consists of an inclined bar of the desired length. The hangers 7 from their upper ends are outwardly inclined. The upper ends of the hangers 7 are connected together by a coupling member 8 provided with a vertically disposed hook 9, to which is connected an adjustable suspending element 10.

The rear side of each hanger abuts against the forward end of the block 3 throughout and each hanger 7 is formed with a transverse opening 11 registering with the opening 6 in the block 3. The lower end of each hanger 7 is flush with the bottom of its associated block 3.

Extending through the registering openings 10 and 6 is a coupling hook 12, having the bill 13 of the hook projecting from the hanger 7 and overlapping the section 2 of the body portion. The bill 13 is of circular contour and has its free end extending into the forward side of the hanger 7. The shank of the coupling hook 13 projects rearwardly from the block 3 and carries a se-

curing nut 14, which abuts against a washer 15. The section 1 of the body portion is mounted on the seat 5 and the washer 15 is of a diameter to confine the section 1 in such position when the coupling hook 12 is arranged in the manner as stated.

Disposed throughout the body portion 1 is a series of radially disposed counter-balanced supports and each of the latter is pivotally connected to and projects outwardly from the section 2 of the body portion, and further is seated upon and projects inwardly from the section 1 of the body portion. Each of said article supports comprises a body portion formed of a single length of wire and carrying at its rear end a counter-balanced weight 16.

The body portion of each of said supports consists of a two-part rear portion 17, which is extended into and secured to the forward end of the weight 16, as at 18. The two parts of the rear portion 17 are arranged in spaced relation and further in parallelism and seat on the section 1. The body portion 25 of each of said supports further includes a two-part intermediate portion 19 and the said parts of said intermediate portion are disposed at opposite inclinations with respect to each other and incline laterally 30 with respect to the portion 17. The intermediate portion 19 has each part thereof, at its forward end, looped around the section 2, as at 20, and merges into one of the parts of a two-part outer portion 21. The loops 35 20 provide a hinge connection between the support and the section 2. The forward portion 21 of the support is looped to provide a spring clamp 22, through which the article 23 is inserted, and when the support 40 is mounted in normal position, as shown in Figure 3, the article 23 is suspended vertically and completely displayed, and removably held by the clamp 23.

The article can be grasped and moved to an inclined or horizontal position when desired and when so moved the support pivots on the section 2, and when the article is released the weight 16 automatically returns the support to the position shown in Figure 50 3. The article can also be swung to an inclined or horizontal position by elevating the weight 16, and when the latter is released

the support is returned to its radial position to suspend the article vertically. The weight 16 permanently tends to maintain the support in radial position, thereby holding the article suspended in a vertical position so as to completely display the same.

It is thought that the many advantages of a holder, in accordance with this invention, can be readily understood, and although the preferred embodiment of the invention is as illustrated and described, yet it is to be understood that changes in the details of construction can be had which will fall within the scope of the invention as claimed.

What we claim is:

1. A holder comprising a body portion formed of an inner and an outer section, spacing blocks arranged between said sections, hangers having their lower ends arranged between said outer section and said spacing blocks, means for securing the lower ends of said hangers, said blocks and said sections together, and a series of radially disposed counter-balanced supports hinged to said outer section, each of said supports seating on and projecting inwardly from said inner section and having its outer end provided with a clamp for detachably connecting the article thereto.

2. A holder comprising a body portion formed of an inner and an outer section, spacing blocks arranged between said sections, hangers having their lower ends arranged between said outer section and said spacing blocks, means for securing the lower ends of said hangers, said blocks and said sections together, and a series of radially disposed counter-balanced supports hinged to said outer section, each of said supports seating on and projecting inwardly from said inner section and having its outer end provided with a clamp for detachably connecting the article thereto, said means overlapping said outer section and each of said blocks provided with a seat for said inner section.

In testimony whereof, we affix our signatures hereto.

GEORGE R. SHEALY.
JOHN K. DERRICK.
